FINISHING APPARATUS

Benjamin A. Franklin, Springfield, Mass.

Application July 15, 1932, Serial No. 622,650

14 Claims. (Cl. 92—68)

This invention relates to improvements in apparatus for finishing the surface of webs from rolls and sheets of material and is directed more particularly to improvements in apparatus for finishing paper and similar materials in web or sheet form.

The principal objects of the invention are directed to the provision of an apparatus adapted to co-operate with co-acting pressure members for finishing paper and like materials. A finishing element or elements and a web or sheet of material such as paper in superposed relation are carried through co-acting pressure members for a finishing operation so that the material is impressed with the characteristics of the element or elements and thereby finished.

The present invention comprehends the provision of apparatus wherein a finishing element or elements is manipulated by a carrier or carriers which carry the same between pressure members such as rolls and the elements may be readily interchanged without danger of the elements being destroyed or injured. According to special features of the invention the apparatus is so constructed and arranged that finishing elements may be readily interchanged so as to not retard production. Altogether it is possible to provide a multiplicity of finishes without the expensive embossed rolls now commonly employed for finishing. Also the expense in changing rolls as is now necessary is obviated since changes in finishes may be accomplished by the simple operation of changing the finishing elements on the carriers.

Various novel features of construction and advantages of the invention will hereinafter more fully appear in the detailed description and the appended claims. For the purpose of illustrating the invention, there is shown in the accompanying drawings typical embodiments of it which in practice will give reliable and satisfactory results. It is to be understood that these embodiments are typical only and that the various instrumentalities of which the invention consists can be variously arranged and organized and that the invention is not limited to the precise arrangement of the instrumentalities shown.

Fig. 1 is a sectional elevational view through an apparatus having the novel features of the invention associated therewith.

Fig. 2 is a front elevational view of the same taken on the line 2—2 of Fig. 1.

Fig. 3 is an enlarged sectional view through the carrier mechanism of the apparatus.

Fig. 4 is a side elevational view of certain de-

tails of construction of the carrier mechanism.

Fig. 5 is a transverse or longitudinal sectional view through a paper drying apparatus having the novel features of the invention associated therewith, and

Fig. 6 is an end elevational view showing the relation of certain of the parts shown in Fig. 5.

Referring to the drawings more in detail the invention will be fully described.

In Fig. 1 there is shown an apparatus embodying the novel features of the invention in association with a pair of co-acting rolls 2 of what may be a calender or finishing machine. It will be understood that the structure of the invention may be used in combination with the co-acting rolls of various types of apparatus, it being intended to make use of co-acting rolls for the finishing operation. For instance it may be used with a pasting machine, drier or other apparatus common to the paper industry.

According to the invention the rolls such as 2 will preferably be operatively connected as by gears 5 which may be located outside frames F in which the rolls 2 are journaled. Endless carriers such as 4 and preferably two for each of the rolls 2 are disposed at opposite ends of said rolls. These are supported outside the rolls 2 by suitable idlers at either side of drums 6 all as indicated in Fig. 1.

The drums and idlers are rotatable in bearings 8 of frames F' which frames may be associated with the frames F. The exact construction in this respect will depend more or less upon the nature of the apparatus with which the apparatus of the invention is to be used.

The endless carriers 4 may be in the form of chains or possibly racks so as to be engageable with and driven by the rolls. Sprockets or gears 10 at opposite ends of the rolls may engage with the chains for the driving function.

When the carriers are made in the form of chains as shown, the said chains may include links such as 16 which are pivoted together in the well known manner as by intermediate links indicated by dotted lines 18 in Fig. 4. Thus the carrier chains will be sufficiently flexible not only to engage with the drivers 10 but to pass around the idlers 6, as well as around other supporting members.

The carriers are so arranged that the lower and upper runs of the upper and lower carriers respectively will be carried forwardly or will be driven by the rolls 2 so that the surface speed thereof will be substantially the same as that of the rolls.

The carriers are arranged to support and carry a finishing element or elements E therebetween and move the same forwardly between the rolls so that material such as paper on or between 5 the elements may be passed simultaneously with the elements through the rolls which exert more or less pressure and thereby impart to the paper or other material a finish to the surfaces thereof which will correspond to the surfaces of the element. The finishing element or elements E may be alike or one element in association with one set of carriers may be different from the element associated with the other and of course the finishing elements may take various forms.

15 As explained in connection with Figs. 3 and 4, the elements for finishing may consist of composite materials, fabrics of various kinds such as linen, burlap or the like and an apron 20 may be disposed thereunder to support the same.

20 In the form of the invention shown in Fig. 3 the aprons 20 may be of relatively thin material such as sheet metal and may overlie the links 16 with finishing elements E superposed thereon. The finishing elements may if desired be adhesively or otherwise secured to the members 20 but will not be necessary in all cases. The members 20 and E may be of course endless or at least 25 opposite ends thereof may be brought into close abutment and secured together in any suitable manner. The elements E may be of different kinds or types of material, and in each element there 30 may be a certain length of a certain type of fabric and then another length of another type of fabric.

35 The members 20 as well as the elements E for finishing the paper are removably attached at opposite marginal edges to the carriers or to the links thereof. This is so they may be easily and readily removed from the carriers for the purpose 40 stated. Various means may be employed for securing the edges of the members 20 and E to the carriers. In the form of the invention shown clamps 31 are provided which have stems 32 slideable in bosses 30 of the links 16 and adjusting 45 nuts 36 in threaded engagement with the lower ends of the stems are adapted to exert endwise pressure thereto and cause the clamps to press the edges of the elements E onto the links or onto the aprons below the elements.

50 In the operation of the apparatus when associated with a pair of co-acting pressure rolls after the manner described the adjacent runs of the upper and lower carriers are moved forwardly so as to carry the finishing elements forwardly between the rolls. The material to be finished such as paper is disposed between the finishing elements so that as the elements at upper and lower 55 sides of the paper are passed through the rolls the pressing action of the rolls causes the paper to be finished or impressed with the characteristics of the finishing elements.

The carriers in the form of chains or otherwise, may be constructed as is usual so one carrier may be disconnected and the other carrier only and its finishing element used. In such a case the upper roll will bear on the paper and press it against the finishing element therebelow which is backed up by the other roll.

70 The modification of the invention shown in Figs. 5 and 6 will now be explained in reference to those figures. In this form of the invention a plurality of rolls 40 are shown which may represent the drums of a drying machine and these are usually arranged so that a web of paper represented by W passes over and under the drums

progressively as it passes through the machine.

According to this form of the invention it is possible to subject the web of paper or other material to a finishing or a surface treating operation as it passes through the drier and at a time 80 when its body and surface may be more or less moist and in that way obtain an efficient finishing action.

85 For this purpose a pair of rolls 44 is disposed adjacent the drier as shown and finishing elements 46 similar to those already described pass over the rolls 44 and other idler rolls 48. These finishing elements 46 as in the former case are carried by carriers such as chains 50 at opposite ends of the rolls.

90 It is of course desirable that the rolls 44 operate at the same rate of speed as the drums 40 and for this purpose one of the rolls 44 such as the lower one may be operatively connected to one of the drums 44 by means of the chain and sprockets 54 and 56 shown in Fig. 6.

95 In this form of the invention the web W is led from a drum 40 upwardly and into contact with the finishing elements 46 so that it is passed therewith between the rolls 44 for the finishing 100 action and then downwardly again into the drier where it continues onwardly in the usual manner.

105 As distinguished from the finishing elements previously referred to in connection with Figs. 1, 2 and 3 the elements may take the form of a relatively stiff member such as a plate having a finishing surface thereon produced by etching or the like. In this case the plate may be carried forwardly by a carrier and with paper super- 110 posed thereon be passed through the rolls for the finishing operation.

115 In another way the carriers may be formed and supported in such a way as to accommodate a circular or semi-circular finishing plate the radius of which may be some larger than that of a roll with which it operates. Since the carriers may be driven by the roll as described the plate will rotate with it.

120 It will be noted that sheets or webs of material from rolls thereof may be operated with equal facility so that and in that way the apparatus is applicable within a wide range for finishing purposes.

125 In all cases the finishing element will preferably travel at the same speed as the surface of the rolls so that there will be no relative movements of the finishing elements, paper and rolls.

130 From the foregoing it will be observed that there is provided an apparatus wherein the finishing operation is performed in an efficient and economical manner and that by means of the invention it is possible to provide a multiplicity of finishing elements, which may be readily interchangeable and provide a multiplicity of finishes 135 without the expense of specially engraved rolls or other expensive equipment.

140 Having described the invention in the form at present preferred what I now desire to claim and secure by Letters Patent of the United States is:

1. The combination with co-acting pressure rolls of apparatus of the class described comprising, endless carriers at opposite ends of one of said rolls operatively connected thereto and driven thereby, and a finishing element secured to and supported by said carriers so as to be carried through said rolls.

145 2. The combination with co-acting pressure rolls of apparatus of the class described com-

- prising, endless carriers at opposite ends of one of said rolls operatively connected to and driven thereby, finishing elements extending between and secured to carriers at the ends of said rolls 5 so as to be carried simultaneously through said rolls by said carriers.
3. The combination with co-acting pressure rolls of apparatus of the class described comprising, endless carriers supported at opposite 10 sides of said rolls and having adjacent runs operatively connected to opposite ends of the rolls whereby said carriers are driven by said rolls and finishing elements having opposite sides secured to said carriers whereby they are carried 15 simultaneously through said rolls.
4. The combination with co-acting pressure rolls of apparatus of the class described comprising, endless carriers at opposite ends of one of said rolls and enclosing the axis thereof, driv- 20 ing connections between said roll and carriers and a finishing element associated with said carriers so as to be moved between the rolls thereby.
5. The combination with co-acting pressure 25 rolls of apparatus of the class described comprising, endless carriers at opposite ends of one of said rolls and enclosing the axis thereof, driv- 30 ing connections between said roll and carriers and a finishing element associated with said carriers so as to be moved between the rolls thereby, the said carriers being provided with means for releasably clamping said element.
6. The combination with co-acting pressure 35 rolls of apparatus of the class described comprising, endless carriers at opposite ends of both of said rolls and enclosing the axes thereof, driv- 40 ing connections between said rolls and carriers and finishing elements associated with said carriers so as to be moved between the rolls thereby.
7. The combination with co-acting pressure 45 rolls of apparatus of the class described comprising, endless carriers at opposite ends of both of said rolls and enclosing the axes thereof, driv- 50 ing connections between said rolls and carriers and finishing elements associated with said carriers so as to be moved between the rolls thereby, the said carriers being provided with means for releasably clamping said element.
8. The combination with co-acting pressure 55 rolls of apparatus of the class described comprising, endless carriers supported at opposite ends and operatively connected to one of said rolls and an apron and a finishing element carried by said carriers so as to be movable thereby through
9. The combination with a plurality of rolls of means for finishing material in web form comprising, a pair of rolls, endless carriers at opposite ends of one of said rolls, driving connections between said rolls and carriers and a finishing element carried by said carriers between said rolls whereby a web of material from said first-named rolls may be passed through said last-named rolls. 80
10. The combination with a plurality of rolls of means for finishing material in web form comprising, a pair of rolls, endless carriers at opposite ends of one of said rolls, driving connections between said rolls and carriers and a finishing element carried by said carriers between said rolls whereby a web of material from said first-named rolls may be passed through said last-named rolls, and driving connections between certain of said first-named and last-named rolls. 85
11. The combination with a plurality of rolls of means for finishing material in web form comprising, a pair of rolls, endless carriers at opposite ends of said rolls, driving connections between said rolls, carriers and a finishing ele- 90 ment carried by said carriers between said rolls whereby a web of material from said first-named rolls may be passed through said last-named rolls, and driving connections between certain of said first-named and last-named rolls. 95
12. The combination with a plurality of rolls of means for finishing material in web form comprising, a pair of rolls, endless carriers at oppo- 100 site ends of said rolls, driving connections between said rolls, carriers and a finishing element carried by said carriers between said rolls whereby a web of material from said first-named rolls may be passed through said last-named rolls. 105
13. The combination with co-acting pressure 110 rolls of apparatus of the class described comprising, a carrier structure operatively connected at opposite ends to opposite ends of one of said rolls and driven thereby, and a finishing ele- 115 ment supported by said carrier structure so as to be carried through said rolls.
14. A combination with a plurality of drying 120 cylinders of apparatus for finishing paper being acted upon by said cylinders comprising, co-acting pressure rolls, a carrier structure opera- 125 tively connected at opposite ends to opposite ends of one of said rolls and driven thereby and a finishing element supported by said carrier structure so as to be carried through said coacting rolls. 130
